HOPPER FEED MECHANISM

Jacob P. Treciokas, Oakville, Conn., assignor to
Scovill Manufacturing Company, Waterbury,
Conn., a corporation of Connecticut

Application July 31, 1943, Serial No. 496,937

13 Claims. (Cl. 218—15.1)

This invention relates to feed hoppers such as used in connection with fastener element setting machines and particularly to an auxiliary hopper used in conjunction therewith.

The particular object of this invention is to provide an auxiliary hopper capable of containing a relatively large mass of elements to be fed to the regular rotary hopper of the type supplied upon automatic fastener setting machines, and also to provide an automatic mechanism for controlling the amount of fastener elements fed from the auxiliary hopper to the rotary hopper.

In practise it has been found that in some instances fastener elements that are set upon garments or other fabric material may be of a relatively large size that have to be fed to the setting station from a hopper on the conventional fastener machines. In such cases it takes but a relatively short time before the regular rotary hopper becomes exhausted of the fastener elements, and therefore requires almost constant attention on the part of the machine operators to see that the hoppers are kept supplied with the fastener elements. If the rotary hopper such as used upon the usual type fastener setting machines was enlarged to accommodate more of the relatively large fastener elements, it was found that too much weight of these elements in the hopper would cause them to jam up rather than to pass out through the orienting slots in the hopper into the raceway leading to the setting station. To overcome this difficulty I provide an auxiliary hopper which will contain a large amount of the fastener elements and set it upon the machine frame in general alignment with the regular machine hopper. A trap door is provided between the auxiliary hopper and the regular rotary hopper that is responsive to the amount of elements disposed in the rotary hopper and allow for only a certain amount of elements to be supplied from the auxiliary hopper into the rotary hopper.

The full nature of this invention along with other objects and various advantages thereof will be more apparent from a consideration of the full description when read in connection with the accompanying drawing, in which—

Fig. 1 is a side elevational view of the regular feed hopper and attached auxiliary hopper;

Fig. 2 is an enlarged vertical sectional view through the same;

Fig. 3 is a further enlarged sectional view through the trap door mechanism taken along the line 3—3 of Fig. 2 and showing the trap door as it appears in full open position;

Fig. 4 is a similar view of Fig. 3 which shows how the trap door is operated by the elements in the rotary hopper; and

Fig. 5 is a plan view of the hopper, per se. Referring now to the drawing wherein like nu-

merals designate like parts throughout the several views, the numeral 10 designates the base plate of the rotary hopper feeding unit which is supported in an elevated and inclined position by means of a bracket 11 attached to any suitable part of the fastener setting machine. The base plate is provided with an integral hub 12 within which is journalled a spindle 13 which in turn supports a rotary feed hopper 14. Specifically the hopper is of cup shape configuration assembled in an inverted manner. The base or upper closed end 15 of the hopper is provided with an inwardly projecting integral hub 16 that is journally mounted upon the spindle 13, but is caused to rotate with said spindle through a friction connection here described. An annular flange 17 projects upwardly from the closed end 15 of the hopper 14 and defines a recess 17a within which is seated a spider type of spring member 18. The upper end of the spindle 13 is provided with a threaded section 13a for threaded receiving a hand nut 19 adapted to be threaded down against the spider spring 18 with a washer 20 interposed therebetween. The pressure that is applied to the spider spring 18 by the threading of the nut 19 upon the threaded spindle 13a determines the frictional connection between the hopper 14 and the spindle 13.

The lower edge of the rotary hopper 14 is formed with an enlarged rim 21 spaced from the adjacent surface of the base plate 10 a distance sufficient to allow a free clearance of the heads of the fastener elements indicated by the numeral 22 to pass therethrough. The rim 21 is provided with a series of oblique discharge ports 21a that during the rotation of the hopper 14 serve to pick up the individual elements 22 in proper position and discharge them into an element guide chute or raceway 23 that leads to the setting station of the machine.

The rotary hopper 14 is adapted to be rotated in one direction only by a pulley and ratchet mechanism carried by the lower end of the spindle 13. Specifically a sleeve 24 is keyed or otherwise made secure to the spindle 13 and rotatable on the sleeve as a pulley 25 which may receive motion by a suitable belt operating off any moving part of the attaching machine. Motion is imparted to the sleeves 24 from the pulley 25 by a spring actuated dog or pawl 26 carried by said pulley 25 and engaging with a ratchet wheel 27 made secure to the sleeve 24. A hand wheel 28 also secured to the sleeve 24 permits for manual rotation of the hopper when necessary or desired independently of the pulley 25.

The mechanism thus far described is an old and well-known construction employed in connection with fastener setting machines and forms no part of the present invention except as it is used in conjunction therewith.

The invention resides particularly in the auxiliary hopper that is located above the rotary hopper and the means for controlling the amount of elements fed from the auxiliary hopper into the rotary hopper. Specifically it comprises a relatively large open end container 30 supported in a stationary manner above the rotary hopper 14 by means of support straps 31 which preferably are permanently secured to the outer walls of the container through the medium of solder and detachably secured to convenient parts of the base plate 10 as by screws 32. The hopper base 15 as originally constructed was provided with an arcuate opening 15a through which the elements were fed directly into the rotary hopper. This opening 15a is now closed by a sheet metal plate disc 33 made secure to the outer face of the hopper base 15, and is therefore caused to rotate with the hopper 14. Within the area of the hopper base opening 15a an opening 34 is provided in the disc plate 33, and the metal out of said opening 34 is formed downwardly to provide a pair of opposed guide walls 35.

Within the disc plate opening 34 and between the walls 35 is adapted to operate an automatically element controlled mechanism that pre-determines the amount of elements that shall be fed from the auxiliary hopper to the rotary hopper. This mechanism comprises essentially a trap door plate 36 having opposed gradually tapering flanges 37 extended along the longitudinal edges thereof. The upper end of the door plate 36 is secured to a hinge member 38 which in turn is detachably secured to the underside of the plate disc 33 as by means of screws 39 engaging in a built up nut portion 40 made secure to one of the hinge flaps. Secured to the underside of the opposite end of the trap door plate 36 is an arcuately shaped downwardly biased tongue member 41 that normally is disposed to ride along the adjacent face of the base plate 10 when there are no elements within the rotary hopper. In this position, such as shown in Fig. 3, the trap door is open and allows for the elements to pass freely from the auxiliary hopper container 30 into the rotary hopper 14.

As the fastener elements are fed into the rotary hopper they, in mass, normally tend to seek a horizontal level and in the usual manner are picked up in proper oriented position by reason of the discharge parts 21a then fed into the chute 23. In case the quantity of elements in the rotary hopper 14 build up too fast or beyond a certain level that would likely jam said hopper, the tongue 41 will be brought into operation and caused to ride over the elements contained therein. The more elements that are fed into the hopper 14 the higher will the tongue 41 rise and eventually close the trap door 36 to preclude any elements passing from the auxiliary hopper to the rotary hopper. As the elements in the rotary hopper become exhausted, the trap door and associated tongue by reason of gravity will drop to allow another supply of elements to pass into the rotary hopper 14 from the auxiliary hopper 30, and thus the action is continuous.

It is to be noted that the trap door 36 throughout its entire movement always has its integral flanges 37 bearing against the opposed guide walls 35 of the opening 15, and this serves to preclude the elements from becoming jammed between the trap door and the edge of the opening 34 in the disc plate 33 when said trap door is being forced to a closed position.

From Fig. 5 it will be observed that the length

of the tongue member 41 extends through an arc of more than 90° and preferably somewhere between 100° and 180° of length. This is for the purpose of assuring that all the elements in the auxiliary hopper will be fed into the rotary hopper. From the fact that the rotary hopper 14 is mounted and operates in an inclined position, obviously, as pointed out above, the element 22, in mass, in both hoppers 14 and 30 will tend to seek a horizontal level, therefore, when the position of the trap door 36 is at the lowermost position relative to the turning cycle of said hopper, the tongue member 41 will extend to a position nearer the upper area within the hopper 14 where there will always be less fasteners or none at all and thus permit the tongue to drop closer to the base plate 10 or in direct contact therewith, and thus allow the trap door 36 to open to its greatest amount. As the hopper 14 rotates and the tongue member is carried to its lower position in its cycle of operation, it will always engage some elements that will have been deposited in the lower area of said hopper and consequently will cause the trap door to partially close as it approaches its uppermost position of the hopper in its rotating cycle. Thus, there will be a sort of fluctuating open and closing motion of the trap door during each revolution of the hopper, and the maximum opportunity for the elements to pass from the auxiliary hopper to the rotary hopper is when the position of the trap door approaches the lowermost position of the hopper cycle such as shown in Fig. 3. This will assure that all the elements in the auxiliary hopper can be drained into the rotary hopper.

Attached to the lower opened end of the auxiliary hopper container is a bevelled reinforcing ring 42 that serves to direct the elements inwardly toward the trap door opening 34 and also acts as a friction member against the adjacent face of the disc plate 33.

It will thus be seen that I provide means wholly automatic in its operation and requiring no mechanical connection with other moving parts of the machine for controlling the feed of the fastener elements from the auxiliary hopper to the rotary hopper, thereby affording a simple and inexpensive arrangement which is perfectly satisfactory and effective in performing the functions required of it and which, moreover, is not apt to get out of order.

While the form of the invention herewith shown and described embraces the preferred embodiment of the same, it is to be understood that the construction may be varied as to mechanical details without departing from the spirit of the invention and the scope of what is claimed.

I claim:

1. In a hopper feed mechanism for a fastener setting machine comprising a support frame, a raceway carried by said frame, said frame providing a hopper base plate disposed in an inclined position, a spindle rotatably mounted in said base plate perpendicular to the face thereof, a rotary hopper having a slotted rim through which the elements are fed to said raceway, said hopper being mounted on said spindle in spaced relation to said base plate, an auxiliary supply hopper mounted above said rotary hopper, said rotary hopper having a closed wall disposed between said rotary hopper and said auxiliary hopper with an opening therein, a trap door pivotally mounted to said wall and operating in

said opening and having means extending to the base plate and capacitated to engage the elements deposited within said rotary hopper to control the position of the door in said wall opening and limit the amount of elements that shall be fed through said opening from said auxiliary hopper into said rotary hopper.

2. In a hopper feed mechanism for a fastener setting machine comprising a support frame, a raceway carried by said frame, said frame providing a hopper base plate disposed in an inclined position, a spindle rotatable in said base plate on an axis perpendicular to said base plate, a rotary cup-shaped hopper having a slotted rim and carried on said spindle in spaced relation to said base plate, the slotted rim being designed to stack the elements disposed in said hopper and feed them properly oriented into said raceway, the closed end or base of said rotary hopper being formed with an opening therein, a fixed auxiliary hopper disposed in general alinement with said rotary hopper, a trap door pivotally mounted to said rotary base and operating within said opening, and an arcuate tongue member attached to the free end of said trap door designed to engage either the adjacent face of the supporting base or the elements contained within the hopper to automatically control the position of the trap door and predetermine the amount of elements that shall be fed from the auxiliary hopper into the rotary hopper.

3. In a hopper feed for a fastener setting machine comprising a rotary hopper, a support plate having an inclined face forming the base of said hopper, a spindle rotatable in said support plate and perpendicular to the inclined face, said rotary hopper being generally cup-shaped, provided with a slotted rim and mounted in an inverted position on said spindle in spaced relation to said inclined face, an auxiliary hopper disposed in general alinement with said rotary hopper, the closed end of said rotary hopper having an opening therein, a trap door hinged to the closed end of said hopper and operating in said opening, and means extending from said trap door member to said support plate responsive to the amount of elements in said rotary hopper to operate the trap door and control the amount of elements fed from said auxiliary hopper through said opening into said rotary hopper.

4. In a hopper feed for a fastener setting machine as defined by claim 3 wherein the opening in the rotary hopper closed end is flanged by depending spaced parallel walls between which the trap door is adapted to operate.

5. In a hopper feed for a fastener setting machine as defined by claim 3 where the opening in the rotary hopper closed end is flanged by depending walls and said trap door is provided with upstanding integral flanges movable in close proximity to said depending walls.

6. In a hopper feed for a fastener setting machine as defined by claim 3 wherein the means attached to the trap door is in the form of an arcuate tongue that extends through an arc of more than 100° and less than 180°.

7. In a hopper feed for fastener setting machines as defined by claim 3 wherein the means attached to the trap door is of a length such that when the trap door in its cycle of movement ap-

proaches its lowermost position relative to the rotary hopper the distal end of said means will extend to a position in proximity to the upper surface of said support plate.

5. 8. In a hopper feed for fastener setting machines as defined by claim 3 wherein the means attached to the trap door is in the form of an arcuate downwardly biased tongue of a length to extend from the trap door to substantially the opposite side of the spindle within the hopper chamber.

10 9. In a hopper feed for fastener setting machines as defined by claim 3 wherein the means attached to the trap door is in the form of an arcuate tongue made of material capable of being bent and holding a set position for adjustment purposes.

15 10. In a hopper feed mechanism in combination with a fastener setting machine having the usual form of inverted cup-shaped rotary hopper mounted on an inclined axis for feeding fastener elements to a raceway leading to the setting station of the machine and wherein the rotary hopper is provided with an opening in its end wall, a trap door pivotally mounted to the hopper end wall, operating in said opening and capacitated to travel with said hopper, a stationary hopper disposed above said rotary hopper in general alinement therewith, and means carried by said trap door extending into the rotary hopper, said means being responsive to the amount of elements deposited in said rotary hopper to predetermine the opening and closing position of said trap door and control the amount of elements fed from said stationary hopper to said rotary hopper.

20 11. In a hopper feed mechanism in combination with a fastener setting machine having the usual form of inverted cup-shaped rotary hopper mounted on an inclined axis for feeding fastener elements to a raceway leading to the setting station of the machine and wherein the rotary hopper is provided with a relatively large opening in its end wall, a plate member secured 40 to said hopper end wall and having an opening flanked by parallel depending flanges projecting through said end wall opening into said hopper, a trap door pivotally mounted to said plate member and operating in said plate opening between 45 said depending flanges, a stationary hopper supported above said rotary hopper in general alinement therewith, and means carried by said trap door extending into said rotary hopper which is responsive to the amount of elements 50 deposited in said rotary hopper to predetermine the amount of elements fed from said auxiliary hopper to said rotary hopper.

55 12. In a hopper feed mechanism as defined by claim 11 wherein a reinforcement ring is attached to the end of the auxiliary hopper generally alined with said rotary hopper for frictional bearing engagement with the adjacent surface of said plate member.

60 13. In a hopper feed mechanism as defined by claim 12 wherein the reinforcement ring is of an inwardly tapering shape to direct the fastener elements in the auxiliary hopper inwardly towards the trap door opening of said rotary hopper.

JACOB P. TRECIOKAS.
